UNITED STATES PATENT OFFICE

CHARLES HOFFMANN, OF NEW YORK, N. Y.

LAMP.

SPECIFICATION forming part of Letters Patent No. 286,006, dated October 2, 1883.

Application filed July 5, 1883. (No model.)

To all whom it may concern:

Be it known that I, CHARLES HOFFMANN, a citizen of the United States, residing at New York, in the county and State of New York, 5 have invented new and useful Improvements in Lamps, of which the following is a specification.

My invention relates to certain improvements on that class of lamps which are described in Letters Patent No. 241,077, granted to Frederick Siemens, May 3, 1881. In the different modifications shown in this patent the illuminating-gas is carried up in close proximity to the regenerative chamber and the air-supply passage is on the outside of the gasways, so that the gas is heated to a higher degree than the air, and while lamps constructed in this manner give perfectly satisfactory results when used for light illuminating-gases, 15 they cannot be used successfully for heavy gases, since such gases, when exposed to a high temperature, deposit a large quantity of carbon, whereby the gasways are obstructed and the successful operation of the lamp is disturbed.

20 The principal object of my invention is a regenerative lamp of the class above described, which can be used for heavy gases as well as for light gases. The peculiar and novel construction of my lamp is pointed out in the following specification, and illustrated in the accompanying drawings, in which—

Figure 1 represents a vertical central section of my lamp in the plane $x x$, Fig. 3. Fig. 2 is a horizontal section in the plane yy , Fig. 1. Fig. 3 is a similar section in the plane zz , Fig. 1. Fig. 4 is a sectional front view of a street-lantern containing one of my lamps on a smaller scale than the previous figures. Fig. 5 is a vertical section of the regulator on a larger scale than Fig. 4. Fig. 6 is a similar section of the block through which the gas passes to the lamp, and which is provided with a passage for carrying off the liquids of condensation.

45 Similar letters indicate corresponding parts.

In the drawings, the letter A designates the regenerative chamber, which connects, by a pipe, B, Figs. 1 and 4, with the pipe C, situated at some distance above the place of combustion. The pipe C is surrounded by a pipe, D, and when the flame has been burning a few seconds the pipe C becomes heated and a strong upward draft is created through the same, so that a suction takes place through the pipe B

and the products of combustion are carried 55 down through the regenerative chamber A and through the pipe B to the pipe D, as indicated by the arrow in Fig. 1.

The illuminating-gas is supplied through the pipe E, which connects, by branch pipes 60 F, with an annular chamber, G, and from this chamber rise four, (more or less) pipes H, which connect with an annular chamber, I, from which the gas escapes through a large number of jets J to the place of combustion. These 65 jets are surrounded by a jacket, K, and they are separated from the regenerative chamber A by a cylindrical shield, L. The jacket K is supplied with cold air through an annular passage, M, which surrounds the gas-supply 70 pipe E, and on the outside of the jacket K is situated a jacket, N, forming an annular space, O, into which the external air can freely pass from below.

On the top of the regenerative chamber A 75 is placed a small cylinder, P, of porcelain or other refractory material, and another similar cylinder, Q, of larger diameter than the cylinder P, is placed on the jacket N.

Between the shield L and the outer surface 80 of the regenerative chamber A is an air-space, K', so that the air which passes up through the interior of the jacket K, which includes the air-space K', is brought in direct contact with the outer surface of the regenerative 85 chamber, while the air-space K' and shield L protect the gas-jets J against the heat which radiates from the regenerative chamber, so that when the lamp is in operation the gas passing up through the gas-jets is never heated 90 to such a degree that a deposit of carbon is formed, while the air which passes through the jacket K to the flame is heated sufficiently high to promote combustion and to produce a bright light.

95 A shield, L', is placed between the gas-pipes H and the outside surface of the regenerative chamber, so that the gas passing through said pipes is protected against the heat radiating from the regenerative chamber.

With the gas-supply pipe E is combined a block, S, (see Figs. 4 and 6,) and a trap, E'', which communicates with the pipe E through a channel, a, bored through block S.

From the channel a extends an oblique 105 channel, b, with a channel, c, which communicates by means of a pipe, E', with the gas-main. The mouth of the channel b is closed

by a screw-plug, *d*. The gas passes through the block *S*, as indicated by the arrows, Fig. 6, and if any condensation takes place in the pipe *E* the condensed liquid runs down into the trap *E''*, which is closed by a cap, *e*, Fig. 4, so that by removing this cap from time to time the condensed liquid can be drawn out and the pipe *E*, which leads to the lamp, is not liable to clog up.

- 10 With the pipe *E'* is combined a regulator, *R*, Figs. 4 and 5. The regulator, which I have represented in the drawings, consists of two chambers, *e' f*. The chamber *e'* communicates through a channel, *g*, with the lower branch 15 of the pipe *E'*, and the chamber *f* communicates with the upper branch of said pipe through a channel, *h*. In the chamber *f* is situated a valve, *V*, which consists of a disk, *i*, and a piston, *j*, the disk *i* being fitted into 20 the upper enlarged part, *k*, of the valve-chamber *V'*, while the piston *j* fits the lower portion, *l*, of said valve-chamber. This lower portion, *l*, communicates through a series of holes, *l'*, with the chamber *e'* of the regulator, 25 and its inner edges are chamfered off, as at *l'*, so that when the piston occupies the position shown in Fig. 5 a limited quantity of gas can pass through into the upper portion, *k*, of the valve-chamber, whence it escapes through 30 a series of holes, *i'*, in the disk *i*. The gas which passes down on the sides of the piston *j* escapes through holes *j'* in this piston. When just sufficient gas passes through the regulator to feed the flame, the valve is kept 35 in suspension by the pressure of the gas; but if the pressure of the gas increases the valve is raised, so as to reduce the gasways at *l'*, and if the pressure of the gas is diminished the valve sinks down, and the gasways at *l'* 40 are increased. The upward movement of the valve is limited by its stem *m* and the regulating-screw *n*, and if the valve drops clear down it can be raised by removing the screw-cap *o* and pressing upon the finger-piece *o'*, 45 the stem of which extends up into the lower part of the valve-chamber *l*. Near the bottom of the channel *h* is a faucet, *h'*, through which the condensed liquid which may accumulate in said channel can be drawn off.
- 50 I do not wish to claim in this application for a patent the gas-regulator above described; neither do I wish to be confined in this present application for a patent to the regulator which I have shown in the drawings, since 55 regulators of various different constructions can be used without departing from the spirit of my present invention.

With the pipe *E'* is combined a shunt-pipe, *E'''*, and suitable stop-cocks are provided, so 60 that the regulator can be shut out and the gas made to pass through the shunt-pipe.

I do not claim as my invention the regenerative chamber, whereby the products of combustion are caused to heat the combustible 65 gas and the air.

What I claim as new, and desire to secure by Letters Patent, is—

1. The combination, substantially as hereinbefore described, with the regenerative chamber, the gas-jets, and the air-jacket *K*, of 70 the shield *L*, interposed between the outside surface of the regenerative chamber and the inner wall of the cylinder containing the gas-jets.

2. The combination, substantially as hereinbefore described, with the regenerative chamber, the gas-jets, and the air-jacket *K*, of 75 the shield *L*, interposed between the outside surface of the regenerative chamber and the inner wall of the cylinder containing the gas-jets, and of the outside jacket, *N*, inclosing the air-jacket *K*.

3. The combination, substantially as hereinbefore described, with the regenerative chamber, the gas-pipes *H*, and the air-jacket 80 *K*, of the shield *L'*, interposed between the outside surface of the regenerative chamber and the gas-pipes *H*.

4. The combination, substantially as hereinbefore described, of the regenerative chamber, the gas-supply pipe *E*, the annular chambers *G I*, the gas-pipes *H*, extending from the chamber *G* into the chamber *I*, the gas-jets *J*, rising from the chamber *I*, the air-jacket *K*, and the shields *L* and *L'*. 90

5. The block *S*, having the vertical channels *a* and *c*, and the diagonal or inclined channel *b*, connecting said channels *a* and *c*, in combination with the trap-pipe *E''*, connected with the channel *a*, and the gas-supply pipe *E'*, connected with the lower end of the channel *c*, and the gas-supply pipe *E*, connected with the upper end of the channel *a*, substantially as described. 100

6. The combination of the regenerative 105 chamber *A*, the gas-supply pipe *E*, having branches *F*, the annular chamber *G*, arranged beneath the regenerative chamber, the annular chamber *I* around the upper portion of the regenerative chamber, the annular series 110 of pipes *H*, connecting the upper and lower annular chambers, the gas-jets *J*, rising from the upper annular chamber, and the air-jacket *K*, substantially as described.

7. The combination of the regenerative 115 chamber *A*, the gas-supply pipe *E*, having branches *F*, the annular chamber *G*, arranged beneath the regenerative chamber, the annular chamber *I* around the upper portion of the regenerative chamber, the annular series 120 of pipes *H*, connecting the upper and lower annular chambers, the gas-jets *J*, rising from the upper annular chamber, the air-jackets *K* and *N*, and the shield *L*, between the regenerative chamber and the gas-jets, substantially as described. 125

In testimony whereof I have hereunto set my hand and seal in the presence of two subscribing witnesses.

CHAS. HOFFMANN. [L. S.]
